UNITED STATES PATENT OFFICE.

THOMAS E. MURRAY, JR., AND JOSEPH B. MURRAY, OF BROOKLYN, NEW YORK.

METHOD OF MAKING METAL HOUSINGS FOR TRANSMISSION-GEAR.

1,363,154.

Specification of Letters Patent. Patented Dec. 31, 1920.

Application filed December 16, 1919. Serial No. 345,233.

To all whom it may concern:

Be it known that we, THOMAS E. MURRAY, Jr., and JOSEPH B. MURRAY, citizens of the United States, residing at Brooklyn, 5 in the county of Kings and State of New York, have invented a certain new and useful Improvement in Methods of Making Metal Housings for Transmission-Gears, of which the following is a specification.

10 In U. S. Letters Patent No. 1,329,135 granted to us January 27, 1920, we have set forth a method of making a metal housing for transmission gear, the said housing consisting of two tubular end portions and in- 15 tegral therewith a circular middle portion of greater diameter than said tubular portions, the said middle portion having in its opposite walls circular openings, which consists in forming from a metal blank a longi- 20 tudinal half section of said housing consisting of two semi-tubular end portions and integral therewith a middle portion of arched form, the opening in said arch being semi-circular, placing a second and 25 similar half section with the straight edges of the semi-tubular portions in registering contact with the straight edges of said first-named section, and electrically welding together simultaneously the pairs of contact- 30 ing edge surfaces of said semi-tubular portions.

Our present invention is a method of producing said object by electrical welding, in which longitudinal half sections are formed, 35 each half section having its middle portion of annular form, so that the welded joint between the half tubular straight sections is continued around the annular middle section.

In the accompanying drawing—
Figure 1 is a side elevation of a housing made in accordance with our present method. Fig. 2 is a top view. Fig. 3 is a section on the line 3, 3 of Fig. 1.

Similar letters of reference indicate like parts.

We form by stamping or pressing from sheet metal, two longitudinal half sections of said housing, each section having two elongated straight semi-tubular portions A, 50 B and a middle enlarged semi-annular portion C. The two sections are placed in suitable electrodes with their edges in registering contact, and upon the passage of the current, said edges are welded together at 55 the joint D, at a single operation.

We claim:

The method of making a metal housing for transmission gear, the said housing consisting of two tubular end portions and an 60 enlarged annular middle portion, which consists in forming, from a metal blank, a longitudinal half section of said housing, consisting of two semi-tubular end portions and integral therewith a middle enlarged 65 semi-annular portion; placing a second and similar half section with its edges in registering contact with the edges of said first-named half section, and electrically welding 70 said edges together.

In testimony whereof we have affixed our signatures in presence of two witnesses.

THOMAS E. MURRAY, JR.
JOSEPH B. MURRAY.

Witnesses:

GERTRUDE T. PORTER,
MAY T. McGARRY.
